UNITED STATES PATENT OFFICE.

RUSSEL B. PRINDLE AND HENRY V. WINSOR, OF NORWICH, NEW YORK.

IMPROVEMENT IN CLOTHES-POUNDERS.

Specification forming part of Letters Patent No. 177,557, dated May 16, 1876; application filed March 24, 1876.

To all whom it may concern:

Be it known that we, RUSSEL B. PRINDLE and HENRY V. WINSOR, of Norwich, in the county of Chenango and in the State of New York, have invented certain new and useful Improvements in Washing-Machines; and do hereby declare that the following is a full, clear, and exact description thereof, reference being had to the accompanying drawings, making a part of this specification, in which—

Figure 1 is a perspective view of our improved apparatus, with one side of the tub or water-reservoir broken away, and a portion of the plunger removed so as to show the interior construction of the latter, and Fig. 2 is a like view of the lower side of said plunger.

Letters of like name and kind refer to like parts in each of the figures.

The design of our invention is to increase the ease and thoroughness with which soiled clothing may be cleansed by percussion; and it consists in the external construction of the plunger and its combination with the reservoir, substantially as and for the purpose hereinafter shown.

In the annexed drawing, A represents our plunger or pounder, constructed, preferably, with a square form in plan view, having vertical sides, and, upon its upper side, having an inward and upward inclination. Within the lower side of the plunger A is formed a recess, B, that is open at its lower side, and between said recess and the upper side of said plunger is provided a second recess, C, which is inclosed at all points except at its lower side, where a number of openings, *c c* and *c*, extend between the same and said lower recess B. A number of vertical cross-bars or pins, D and D, provided at suitable points within the recess B, complete the interior construction of the plunger, which is fitted into a reservoir, E, that corresponds therewith in horizontal shape, but has such dimensions as to leave a space of about one inch between the sides of said parts. To each corner of said plunger is attached a lug, *a*, which loosely fills the space between the same and the sides of said reservoir, and, in connection with the other lugs, operates as a guide to hold said plunger in a central position within said reservoir. To the upper side, at the center of

the plunger A, is secured a bar, F, which extends vertically upward beyond the upper edge of the reservoir E, and, at its upper end, is bifurcated, so as to permit of the insertion between its arms of one end of a lever, G, which lever is connected therewith by means of a pin, H, that passes horizontally through said parts. The lever G is pivoted near its longitudinal center within a forked standard, I, by means of a pin, K, which passes horizontally through openings in said parts, and, in order that said lever may be placed at a higher or lower point to suit the convenience of the operator, a number of pin-openings, *i* and *i*, are provided within said standard. Similar provision is made for changing the relative vertical position of the plunger A by providing a number of openings, *f* and *f*, within the bar F, into each of which the pin H may be placed.

The operation of the device is as follows: Hot soap-suds and soiled clothing being placed within the reservoir, the plunger is placed in position upon the top of said clothing, and the operating-lever connected, after which the latter is manipulated so as to cause said plunger to be continuously raised and let fall upon the contents of said reservoir. At the instant of the impact of the plunger upon the wet clothing, the air contained within the recesses B and C is compressed, so as to permit said recess B to be partly or wholly filled with water; but immediately thereafter said air expands to its original volume, and forces said water downward through said clothing. The result of such percussion and the rebound of the compressed air, is to cause so rapid a circulation of water through the soiled clothing, as to speedily cleanse the same from all impurities. Such water as passes upward between the sides of the plunger and reservoir is turned outward and downward by the inclined upper surface of said plunger as soon as the latter commences its upward motion.

The air-chamber C serves to lessen the weight of the plunger, which, from its large horizontal dimensions, would otherwise be difficult to manage, and at the same time said chamber renders said plunger buoyant when submerged within the water, and operates to give to the same an upward impulse, which

materially lessens the labor required to raise it.

As the plunger substantially fills the interior of the reservoir horizontally, it will be seen that at each downward movement it impinges upon almost the entire upper surface of the contents of the latter, sufficient space only being left between its edges and the sides of said reservoir to permit water to pass between the same when said plunger is being operated, by which means, at each downward stroke of said plunger, the entire contents of said reservoir is operated upon, and such an agitation produced as to speedily cleanse the clothing.

Having thus fully set forth the nature and merits of our invention, what we claim as new is—

In combination with the reservoir E, the plunger A, constructed with a conical upper side, provided at each corner with a lug, a, which prevents contact between said plunger and reservoir, and arranged to have a vertically-reciprocating motion within the latter, substantially as and for the purpose set forth.

In testimony that we claim the foregoing we have hereunto set our hands this 4th day of March, 1876.

RUSSEL B. PRINDLE.
HENRY V. WINSOR.
